METHOD AND APPARATUS FOR PRODUCING CURLLED OR CRIMPED GLASS WOOL

Paul O. E. Friedrich, Millville, N. J., assignor to firm Friedrich & Dimmock, New York, N. Y., a firm composed of Paul O. E. Friedrich and Frank L. Dimmock

Application January 26, 1934, Serial No. 708,529

5 Claims. (Cl. 49—7)

This invention relates to a method and apparatus for producing curled or crimped glass wool and has for an object to provide an improved method and apparatus for taking a flat sheet of glass thread and permanently curling, crimping or waving the thread and further for dividing the sheet into a plurality of strands so as to produce a plurality of permanently waved, curled or crimped strands of glass wool.

10 A further object of this invention is to provide an apparatus for permanently waving a flat sheet of glass thread and an adjustable cutting means for dividing the flat sheet into a plurality of strands just as it is being fed through the curling, crimping or waving means.

15 With the foregoing and other objects in view, as will hereinafter become apparent, this invention comprises the constructions, combinations and arrangements of parts hereinafter set forth, 20 disclosed and shown on the accompanying drawing. In the drawing,

Figure 1 is a front view of the invention,

Figure 2 is a rear view of the invention, and

25 Figure 3 is a sectional view taken on line 3—3 of Figure 2.

There is shown at 10 the apparatus constituting this invention, the apparatus 10 being mounted or supported on any suitable space 11.

The apparatus 10 comprises a pair of supporting frame members 12 and 13 secured to the base 11 as by bolts 15, and secured to each other by a pair of rods 16 and 17. A pair of interwoven corrugating rolls 18 and 19, mounted on shafts 20 and 21 are supported in interweaving contact 35 one above the other by means of suitable bearings 22 extending through the frame 12 and 13. Gear wheels 23 and 24 keyed on the shafts 20 and 21 are meshed with each other so as to insure the same rate of rotation of both rolls 18 and 19, it being observed that the gear wheels 23 are provided with the same number of teeth as the roll 18 is provided with corrugations, and likewise that gear wheels 24 are provided with the same number of teeth as there are corrugations on the roll 19, thus insuring that the corrugations on the rolls 18 and 19 will always properly interweave with each other.

In order to provide rotation of the rolls 18 and 19 one of the shafts, as for instance the lower 50 shaft 20 is extended at one side and provided with a grooved wheel 25, which is rotated by a belt 26 from any suitable source of power. Suitable means for heating the rolls 18 and 19 are provided and preferably consists of a plurality of gas jets 27 and 28 placed in gas pipes 29 and 30

supported by the frame members 12 and 13, it being observed that the gas jets 27 are placed below and closely adjacent the lower corrugating roll 18, and that gas jets 28 are placed above and closely adjacent the upper corrugating roll 19. The flames from the gas jets 27 and 28 are thus in a position to heat the corrugating rolls 18 and 19 while the same are in operation.

A table 31 is provided for feeding a flat sheet of glass thread through the corrugating rolls 18 and 19, one edge of the table 31 terminating closely adjacent the interweaving lines of contact between the rolls 18 and 19. The table 31 is supported on the frame members 12 and 13 by means of a pair of angulars 32 on the upper rod 17 and a pair of braces 33 on the lower rod 16. A rod 35 triangular in cross section is supported on the frame members 12 and 13 below the table 31 and adjacent the edge 34 nearer the corrugating rolls 18 and 19.

One face of the rod 35 is provided with a plurality of short knife blades 36 and the table 31 is provided with a corresponding plurality of slots 37. The end of the rod 35 is provided with a lever 38. Manual movement of the lever 38 to the position 38' moves the knife blades 36 through the slots 37 to the position 36', thereby dividing the flat sheet of glass thread 40 into a plurality of individual strands just as the sheet 40 is about to be fed in between the corrugating rolls 18 and 19.

The method of operation is as follows:

Flat sheets of glass thread 40 of predetermined lengths are placed on the table 31. The lever 38 is placed in the position 38' thereby bringing the knife blades 36 through the slots 37 to the position 36' and dividing the flat sheet of glass thread 40 into a plurality of individual strands, the width of the individual strands being determined by the spacing between the blades 36 and the slots 37.

The individual strands, each strand consisting of a group of threads, are then fed through the interweaving lines of contact between the rolls 18 and 19, the gas jets 27 and 28 having been lighted 45 previously so as to bring the rolls 18 and 19 to the desired temperature and to maintain them at this desired temperature. As the strands pass between the rolls 18 and 19, the corrugations on the rolls 18 and 19 press alternately on opposite 50 sides of the strands, and these corrugations being heated they momentarily soften the threads of the individual strands, which immediately reharden again so as to permanently retain the curved, crimped or curled shape as shown at 42. 55

Thus the apparatus and method just described takes a flat sheet of glass thread and produces a plurality of permanently waved, curled, crimped or corrugated individual strands of glass wool.

5 The novel features and the operation of this device will be apparent from the foregoing description. While the device has been shown and the structure described in detail, it is obvious that this is not to be considered limited to the exact 10 form disclosed and that any changes may be made therein within the scope of what is claimed without departing from the spirit of the invention.

Having thus set forth and disclosed the nature 15 of this invention, what is claimed is:

1. In a method of producing curled or crimped strands of glass wool, the steps of longitudinally dividing a flat sheet of glass wool into a plurality of strands, and of imparting a permanent 20 wave formation to the divided strands.

2. A method of producing curled or crimped strands of glass wool, consisting in simultaneously dividing a flat sheet of glass thread into a plurality of strands longitudinally of the threads, 25 corrugating the divided strands simultaneously by applying pressure alternately to opposite sides of the strands, and simultaneously applying heat to said divided strands as the pressure is being applied whereby the divided individual strands 30 will retain a permanent wave formation.

3. An apparatus for producing curled or crimped glass wool, comprising a pair of interwoven corrugated rolls, means for rotating said corrugated rolls, means for heating said corrugating rolls as said rolls are being rotated, a frame for supporting said corrugating rolls, said heating means and said rotating means, a table for feeding a flat sheet of glass thread through said corrugating roll, one edge of said table being adjacent the interweaving lines of contact between said roll, said table being supported on said frame, and means cooperating with said table adjacent and preceding said interweaving lines of contact, dividing the flat sheet of glass 40 thread into a plurality of strands.

45

4. An apparatus for producing curled or crimped glass wool, comprising a pair of interwoven corrugated rolls, means for rotating said corrugated rolls, means for heating said corrugating rolls as said rolls are being rotated, a frame for supporting said corrugating rolls, said heating means and said rotating means, a table for feeding a flat sheet of glass thread through said corrugating roll, one edge of said table being adjacent the interweaving lines of contact between said roll, said table being supported on said frame, means cooperating with said table adjacent and preceding said interweaving lines of contact, dividing the flat sheet of glass thread into a plurality of strands, said means comprising a rod supported on said frame, a plurality of longitudinal slots extending through said table, a plurality of knife blades on said rods, and means for adjusting said rods to cause said knife blades to extend through said slots.

5. An apparatus for producing curled or crimped glass wool, comprising a pair of interwoven corrugated rolls, means for rotating said corrugated rolls, means for heating said corrugating rolls as said rolls are being rotated, a frame for supporting said corrugating rolls, said heating means and said rotating means, a table for feeding a flat sheet of glass thread through said corrugating roll, one edge of said table being adjacent the interweaving lines of contact between said roll, said table being supported on said frame, means cooperating with said table adjacent and preceding said interweaving lines of contact, dividing the flat sheet of glass thread into a plurality of strands, said means comprising a rod supported on said frame, a plurality of longitudinal slots extending through said table, a plurality of knife blades on said rods, and means for adjusting said rods to cause said knife blades to extend through said slots, said means comprising a lever secured to said rod exterior of said frame.
